UNITED STATES PATENT OFFICE

CHARLES O. GUERNSEY, OF PHILADELPHIA, PENNSYLVANIA

INTERNAL-COMBUSTION ENGINE

Application filed September 22, 1928. Serial No. 307,721.

This invention relates to the details of cylinder construction in an internal combustion engine, and is more particularly concerned with the problem of adequately cooling the cylinder at the juncture between the cylinder head and the cylinder block, and adjacent the head of the piston.

An object of the invention therefore, is to provide adequate cooling means between the juncture of the cylinder head and the cylinder block.

Another object is to provide adequate cooling means adjacent the top of the piston.

Another object is to provide adequate cooling means between the juncture of the cylinder head and the cylinder block, and adjacent the top of the piston.

Another object of the invention is to provide a cylinder sleeve having an offset flange at its upper end.

Another object is to provide a flanged cylinder sleeve, which flange is interposed between the cylinder head and the cylinder block.

Still another object is to provide a cylinder sleeve flanged at its upper end, the flange being interposed between the cylinder head and the cylinder block; the flange, the cylinder head, and the cylinder block having a cooling system extending therethrough.

Yet another object is to produce a new and improved cylinder construction.

Other objects will appear hereinafter.

In the drawings:

Fig. 1 is a vertical section of the preferred form of my invention;

Fig. 2 is a view along the line 2—2 of Fig. 1;

Fig. 3 is a transverse section along the line 3—3 of Fig. 1, and illustrates the bosses provided for the spark plugs;

Fig. 4 is a section along the line 4—4 of Fig. 1 and depicts the vertical passages, provided in the flanged portion of the cylinder sleeve for the reception of a cooling medium.

Fig. 5 is a vertical section of another form of my invention; and

Fig. 6 is a view taken along the line 6—6 of Fig. 5.

Looking more particularly at Figs. 1—4, the

cylinder block is illustrated at 1, while the cylinder head is broadly indicated by the reference numeral 2. The cylinder sleeve is shown at 3, and is provided at its upper end with a flanged portion 4. The cylinder block is mounted on a suitable frame 5.

Within the cylinder sleeve is carried a piston 6, which is connected in the usual way to a connecting rod 7, attached to the customary crank shaft 8. A pump or other suitable means 9 supplies a cooling medium to the passageway 10, interposed between the walls of the cylinder block and the cylinder sleeve, thus forming a water jacket.

Ordinarily the cooling medium is passed directly from the water jacket around the cylinder block into a suitable jacket provided around the cylinder head. Inasmuch as the cylinder head and the cylinder block are customarily in juxtaposition and the cylinder sleeve is shouldered into the cylinder block at its top, and since the combustion chamber and spark plugs are placed in the cylinder head, there is found to be a considerable area to which the cooling water does not have access. As a result of this prior construction, local heating of the top of the cylinder sleeve is caused, which in turn tends to increase the temperature of the piston head. To avoid this intense local heating, the structure shown has been provided.

As will be seen, the cylinder sleeve 3 is provided at its upper end with the flange 4. This flanged portion is interposed between the top of the cylinder block and the lower surface of the cylinder head. Bosses 11 may be provided in the flanged portion for the reception of spark plugs 12. The flange 4 has suitable channels 13 and 14 extending therethrough, for the passage of the cooling fluid from the channel 10; and these in turn communicate with the passageways 15 in the cylinder head.

In this manner, there is formed a complete circuit for a cooling medium, the medium being passed through pump 9, through channels 10, through passageways 13 and 14 into passageways 15, and thence through opening 16 back to the pump. Exhaust and intake

ports 17 and 18 are provided in the cylinder head, the ports being closed by suitable valves 19.

As will be noted in Fig. 1, the connecting rod 7, shown at the top extremity of its stroke, 5 terminates short of the lower face of the cylinder head. Thus a space 20 exists between the top of the piston 6 and the bottom face of the cylinder head. This space, which is immediately adjacent the spark plugs 12, 10 comprises the combustion chamber.

As a result of this invention, the local hot spot at the top of the piston is avoided, the water-jacketing in the flanged portion of the cylinder sleeve lining being adjacent this 15 point, and the amount of water carried around the combustion chamber is considerably increased. The further advantage exists that the cylinder head need not contain the combustion chamber, but can be made flat 20 at the bottom face.

In the form shown in Fig. 5, the cylinder sleeve 21 has a flange 22 at its upper end, which flange is successively outturned, down-turned, and inturned; the edge of the flange 25 terminating short of the wall of the sleeve. This flange rests on an annular ledge formed on an inner wall of the cylinder block 24, which in turn, is supported by suitable 30 means such as a frame 25.

A piston 26 rides within the cylinder sleeve and is connected by any suitable means such as a pin 27 to the conventional connecting rod 28, which drive the usual crank shaft 29. 35 The flange 22, terminating as it does short of the wall 21, thus provides a small opening 30 which joins an annular water passage 31 to the passageway 32, formed by the flange 22. Any desirable means may be utilized to 40 force the cooling medium through the channels. As shown, these means comprise the pump 33.

Resting on the top of the flange 22 and the circumferential edge of the cylinder block, 45 is the cylinder head 34. A plurality of suitable orifices 35 and 36 connect the passageway 32 with passageways 37 formed in the cylinder head. The usual exhaust and inlet 50 openings 38 and 39 are provided in the cylinder head and these openings are closed by suitable valves 40. A combustion chamber 41, similar to combustion chamber 20, is provided in the top portion of the cylinder sleeve.

In this construction, the fit between the 55 sleeve and the cylinder jacket is on the outer diameter of the water jacket portion of the sleeve, which makes for even freer passage of water between the water jacket and the 60 jacketed portion of the sleeve 21. In this case however, the fitting of spark plugs in this portion is somewhat more difficult and the precise manner is not shown in the figure.

As will be readily understood, the invention 65 is susceptible to numerous modifications,

and it is intended that it be limited only by the scope of the appended claims.

I claim:

1. In an internal combustion engine, a cylinder block, a cylinder head, a cylinder sleeve 70 having at its upper end an outwardly extending flanged portion interposed between said cylinder block and said cylinder head, bosses in said flanged portion for the reception of spark plugs, and cooling means with- 75 in said flanged portion.

2. In an internal combustion engine, a cylinder block, a cylinder head and a cylinder sleeve within said cylinder block, and having at its upper end an outwardly extending 80 water jacketed portion, said portion having means therein for the reception of spark plugs.

3. In an internal combustion engine, a cylinder block, a cylinder head, a cylinder sleeve 85 in said cylinder block and having an outwardly extending flanged portion at its upper end, a combustion chamber in said sleeve, and spark plugs in said flanged portion.

4. In an internal combustion engine, a cylinder block, a cylinder head, a cylinder sleeve within said cylinder block and terminating at its upper end in an outwardly extending water jacketed portion, a piston within said 90 sleeve, said piston terminating at the extremity of its stroke short of the cylinder head, thus defining a combustion chamber within said cylinder sleeve adjacent said flanged portion, and means within said flanged portion for the reception of spark 95 plugs.

5. In an internal combustion engine, a cylinder block, a cylinder head, a cylinder sleeve within said cylinder block and terminating at its upper end in an outwardly extending 100 flanged portion interposed between said cylinder block and said cylinder head, a piston in said cylinder sleeve, said piston terminating at the extremity of its stroke short of the cylinder head, thus defining a combustion chamber within said sleeve adjacent the flanged portion, means within said flanged portion for the reception of a spark plug, a passageway extending through said flanged portion, water jacketing about said cylinder block and about said cylinder head, said passageway connecting said water jacketing and forming a closed water circuit, and means for forcing a cooling medium through said 110 circuit.

6. In an internal combustion engine, a cylinder block having an internal annular flange adjacent its upper extremity, a cylinder head, a cylinder sleeve within said cylinder block 115 and terminating at its upper end in an outwardly extending hollow flanged portion, said flanged portion resting on said annular flange, water jacketing about said cylinder sleeve and said cylinder head, and a passage- 120

way connecting said water jacketing to the interior of said hollow flanged portion.

7. In an internal combustion engine, a cylinder block having an internal annular flange adjacent its upper end, a cylinder head provided with water jacketing, a cylinder sleeve within said cylinder block and having at its upper end an outwardly extending hollow annular flange, said flange resting on said internal annular flange, water jacketing about said cylinder sleeve, a piston in said sleeve, said piston terminating at the extremity of its stroke short of said cylinder head, passageways connecting together the water jacketing and the interior of the hollow flanged portion, thus forming a closed circuit, and means for forcing a cooling medium through said circuit.
